SAFETY EQUIPMENT FOR BOATS

Morris Mandel, Chicago, Ill.

Application June 9, 1937, Serial No. 147,223

5 Claims. (Cl. 9—4)

My invention relates to safety apparatus for boats and like devices.

My invention relates more particularly to safety apparatus for boats capable of being employed to assist in keeping boats afloat during stormy weather and high waves.

The principal object of my invention is to provide an improved apparatus capable of being secured to open boats so that the same can be comparatively enclosed in an emergency such as a storm or high wind with its resultant high waves.

A further object is to provide an improved safety apparatus of the type described capable when not in use of being collapsed and secured upon the gunwales of the boat.

A further object of the present invention is to provide apparatus of the class described that may be opened in such a manner that the same will meet over the center of the boat where it can be secured together and rigidly held in this position.

A further object is to provide improved means associated with the edges of the side members whereby an airtight and water-tight seal can be made by the meeting edges.

A further object is to provide improved means associated with the side members whereby valved airports may be employed to permit air to enter the enclosed boat whenever the side members are locked in their upright position.

Other objects and advantages will be more apparent from the following description wherein reference is had to the accompanying two sheets of drawings, upon which:

Fig. 1 is a plan view of the usual type of motor boat with my improved apparatus secured upon the gunwales thereof;

Fig. 2 is a side elevational view thereof with the closure members in the open position providing a complete cover for the boat;

Fig. 3 is a vertical cross-sectional view thereof taken generally on the lines 3—3 of Fig. 2;

Fig. 4 is a fragmentary sectional view through the back member showing the manner in which the same is mounted upon the rear edge wall of the boat;

Fig. 5 is an enlarged fragmentary view of a portion of one of the side members;

Fig. 6 is a vertical sectional view taken along the line of the support braces and shown along line 6—6 of Fig. 5;

Fig. 7 is a fragmentary view with the gunwale of the boat in section showing the manner in which the side members are fastened upon the boat;

Fig. 8 is a fragmentary sectional view through the meeting edges of the side members taken generally on the line 8—8 of Fig. 3, and

Fig. 9 is a fragmentary view of a portion of

the flexible side members showing the valved air-ports.

While it will be understood that the flexible covering members may be employed with boats of any size, I have illustrated the same in connection with the usual motor boat 10 which is provided with the motor 12 that is connected in a driving relation to the propeller 14 at the back of the boat. I provide a steering wheel 16 connected in the usual manner to the rudder 18 which is also situated at the back of the boat. The boat may be formed with the hull portion 20 and a floor 22 which covers the drive shaft 24 for the propeller and the steering means 26 extending to the rudder. It will be noted that the boat is provided with the two side gunwales 28 and 30 and the rear edge gunwale 32.

Upon each of the gunwales 28 and 30, I mount a plurality of brackets 32 which securely hold the lower end 34 of the flexible side members 36 and 38. The side members as shown in the enlarged fragmentary view Fig. 5 may be formed of flexible water-proof canvas or other suitable material and be provided with a plurality of openings 40 of a desired size and shape within which a plurality of windows 42 are adapted to be mounted. The windows 42 are also preferably flexible and are therefore constructed of mica or other similar material that is transparent and flexible. These are adapted to be secured in place by sewing around the peripheral edge of the same and form a comparatively water-proof seal around the edge of the opening 40. It will be noted in Fig. 2 that the windows 42 are provided in upright and longitudinal rows so that a comparatively unobstructed view may be obtained in any direction.

I provide means for supporting the side members 36 and 38 in a raised position and this means may be in the form of strap members 45 and 46 which are pivotally mounted on suitable pins and so formed that when they are raised to the position shown in Figs. 6 and 7 they form a comparatively straight wall which is capable of supporting the flexible side members 36 and 38.

Suitable locking arms 48 and 50 are provided at alternate joints so that the entire side wall can be rigidly supported in an upright position, or the arms may be sideways and the entire side section collapsed as shown in dotted lines in Fig. 7. When the side wall sections are collapsed as shown in Fig. 7 they are adapted to be covered by a flexible water-proof cover member 52 which is secured to the lower edge of the gunwale and folded over the same with its outer edge fastened on the pin members 54.

With the side sections in the raised position as shown in Fig. 3 it is desirable to have a more or less water-proof joint between the meeting edges. Accordingly I provide a flexible member preferably formed of rubber, having bulged por-

tion 56 secured along the entire front edge 57 of the side section 36 and a similar resilient member 58 having a complementary socket portion 59 to engage the bulge 56. In this manner and when 5 the strap member 60 secured to the member 38 is fastened over the pin 62 secured to the member 36 the sections will be fastened together in a comparatively water-proof manner. It will be understood that the strap members 60 are placed 10 at a plurality of points throughout the length of the side members 36 and 38.

With the back collapsible member 62 secured by suitable strap members 64 to the side members 36 and 38 it will be apparent that a complete 15 closure has been provided for the boat.

With the construction as thus provided, and with the boat enclosed in the manner described, it is necessary to provide means for permitting air to enter the boat for the benefit of the passengers. Accordingly, in some of the windows 42, 20 I provide the valve members 67 which are formed with a plurality of vane portions 69 that co-operate with the similarly shaped openings 70 to permit air to enter the enclosure. Suitable handles 72 at the center of the valve may be employed to rotate the same to regulate the size of the opening.

It will be obvious that within limits as to size and shape of boats, the invention is adaptable to 30 any and all types of craft which are found upon the water. A particularly advantageous adaptation will be to fishing boats and similar craft frequently upon the water and usually required to stay at sea a certain length of time regardless 35 of weather conditions. With my invention the safety of these boats is assured.

While I have illustrated and described a specific embodiment of the invention, it will be apparent to those skilled in the art that numerous 40 changes and modifications may be made in the exact details shown, and I do not wish to be limited in any particular; rather what I desire to secure and protect by Letters Patent of the United States is:

45 1. A safety appliance for boats comprising collapsible flexible side members fastened in a collapsed condition on the top of the gunwales of a boat, a waterproof cover member enclosing the same, a collapsible flexible back member fastened in a collapsed condition on the top of the back edge members of the boat, a waterproof cover member enclosing the same, means comprising rigid strap members for supporting said flexible side and back members in a raised position, each of said side members having a resilient meeting edge, fastening means to hold said edges together in a raised position, and means fastening said back member along its edges to said side members to form an enclosure over said boat.

60 2. A safety appliance for boats comprising collapsible flexible side members fastened in a collapsed condition on the top of the gunwales of a boat, a waterproof cover member enclosing the same, a collapsible flexible back member fastened 65 in a collapsed condition on the top of the back edge members of the boat, a waterproof cover member enclosing the same, means comprising rigid strap members for supporting said flexible side and back members in a raised position, each 70 of said side members having a resilient meeting edge, fastening means to hold said edges together

in a raised position and means fastening said back member along its edges to said side members to form an enclosure over said boat, said fastening means comprising hook members secured to one side member and hook engaging members 5 secured to the other side member.

3. A safety appliance for boats comprising collapsible flexible side members fastened in a collapsed condition on the top of the gunwales of a boat, a waterproof cover member enclosing the same, a collapsible flexible back member fastened in a collapsed condition on the top of the back edge members of the boat, a waterproof cover member enclosing the same, means comprising rigid strap members for supporting said flexible 15 side and back members in a raised position, each of said side members having a resilient meeting edge, fastening means to hold said edges together in a raised position and means fastening said back member along its edges to said side members 20 to form an enclosure over said boat, said fastening means comprising hook members secured to one side member and hook engaging members secured to the other side member, said side members and back member formed with a plurality 25 of rows of flexible window portions, some of said window portions arranged to be opened to permit access of air into said boat.

4. A safety appliance for boats comprising collapsible flexible side members fastened in a collapsed condition on the top of the gunwales of a boat, a waterproof cover member enclosing the same, a collapsible flexible back member fastened in a collapsed condition on the top of the back edge members of the boat, a waterproof cover 30 member enclosing the same, means comprising rigid strap members for supporting said flexible side and back members in a raised position, said strap members having pivotally mounted arm portions for holding the same in a rigid 35 position, each of said side members having a resilient meeting edge, fastening means to hold said edges together in a raised position, and means fastening said back member along its edges to said side members to form an enclosure over said 45 boat.

5. A safety appliance for boats comprising collapsible flexible side members fastened in a collapsed condition on the top of the gunwales of a boat, a waterproof cover member enclosing the same, a collapsible flexible back member fastened in a collapsed condition on the top of the back edge members of the boat, a waterproof cover member enclosing the same, means comprising rigid strap members for supporting said flexible 55 side and back members in a raised position, each of said side members having a resilient meeting edge, fastening means to hold said edges together in a raised position and means fastening said back member along its edges to said side members to form an enclosure over said boat, said fastening means comprising hook members secured to one side member and hook engaging members secured to the other side member, said side members and back member formed with a 60 plurality of rows of flexible window portions, some of said window portions arranged to be opened to permit access of air into said boat, said rigid strap members arranged between rows of flexible window portions in said side and back members. 70

MORRIS MANDEL.
